UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF ILLINOIS.

METHOD AND APPARATUS FOR CONSTRUCTING PLASTER BOARD.

Application filed January 13, 1921. Serial No. 437,062.

My invention belongs to that general class of inventions relating to the manufacture of plaster or wall board, and relates particularly to the method and apparatus for constructing an improved board. The invention has among its objects the production of an improved board and an improved method of constructing the same. It also has among its objects the production of a simple, efficient, durable and satisfactory apparatus for carrying out the method herein described. Many other objects and advantages of the construction herein shown and described will be obvious to those skilled in the art 15 from the disclosure herein given.

To this end my invention consists in the novel construction, arrangement and combination of parts herein shown and described, and more particularly pointed out in the 20 claims.

In the drawings, wherein like reference characters indicate like or corresponding parts,

Fig. 1 is substantially a view in elevation and partly in section, illustrating one form 25 and partly in section, illustrating one form of apparatus suitable for carrying out the method;

Fig. 2 is a similar view illustrating a slight modification in the same for producing 30 a reinforced edge;

Fig. 3 is a top elevation of the trimming mechanism shown in Figs. 1 and 2;

Fig. 4 is a view similar to Fig. 1, illustrating another modified form;

Fig. 5 is a similar view illustrating another form of apparatus;

Fig. 6 is a view in elevation illustrating the trimming mechanism shown in Figs. 4 and 5;

Fig. 7 is a sectional view of the board under the forming rolls in Fig. 1;

Fig. 8 is a sectional view of a portion of a board with the edges not reinforced, which may be produced with the apparatus shown 45 in Figs. 1 and 4;

Fig. 9 is a similar view of a board having a reinforced edge and which may be constructed on the apparatus shown in Fig. 2 and 5;

Fig. 10 is a view in elevation illustrating 50 one type of cutting mechanism;

Fig. 11 is a plan view of the same; and Fig. 12 is an end elevation of the same.

Referring to the drawings, it may be first mentioned that the boards shown in 55 Figs. 8 and 9 are substantially similar, except that the board shown in Fig. 9 is reinforced at the edges by strips, for example trimmings removed from the sheets. Plaster boards of various types have been heretofore 60 manufactured, some with what may be termed "raw" or "unbound" edges, and others with "bound" edges, the board proper consisting of a body of plaster or like material provided with covering sheets on the 65 two faces. Some types of boards have been manufactured in which sheets are imbedded in the body or the body made up of alternate sheets of imbedded covering material 70 and plaster.

Generally, in making plaster board, a plastic mass is dumped on a moving sheet of paper, which forms one cover sheet, and thereafter a second cover sheet applied, the 75 board being generally passed through forming rolls which form the board and determine its thickness. Various other appliances and apparatus may be employed to finish the product. In some cases, as previously mentioned, the edges at the sides are 80 bound by folding one of the sheets or its equivalent over the opposite side of the board so as to enclose the edge and produce a finished appearance.

In the manufacture of plastic board, the 85 plaster mass dumped on the paper is, of course, to a large extent moist, as it must be of a consistency that it may be spread and be formed in the forming of the board; or as it may be explained, it is in an unstable 90 condition.

Various kinds of paper or other covering material have been employed, and various conditions are met with as a result of this, owing to the expansion and contraction of the paper and board, which may vary depending upon the materials employed, as well as to a weaving of the paper 95 as it enters into the manufacture of the board. Also, the paper is usually supplied 100 from rolls, and there may be slight variations in the width of the paper, either in the different rolls or in the same roll, and frequently in handling the roll the paper becomes slightly telescoped. The paper 105 contracts or expands in shipment or storage

and the edges get abraded in handling. In the methods previously carried out, it has been extremely difficult to produce a uniform production, owing to the reasons mentioned, and placing the upper sheet directly over the bottom sheet, whereby their edges are aligned or arranged one directly above the edge of the other sheet, so that either a poorly finished product was obtained, or 10 it was necessary to go to the expense of trimming the manufactured board after it had passed the forming rolls.

In my present method herein described, I trim the edges of the paper before passing 15 through the machine, and preferably in advance and comparatively close to the forming rolls so that the trimming mechanism may be so controlled and manipulated as to trim the sheets and bring them with 20 their edges exactly in alignment, so that when the board is taken from the machine, the edges are straight with the edges of the paper, arranged one directly above the other. Where the edges are to be reinforced, as will be hereinafter described, 25 there is positively no waste, as the trimmings are fed in so as to register with the outer covering sheets, thereby reinforcing the board at the edges, and producing an especially strong product.

Referring to the drawings, particularly Fig. 1, 7 represents a table, support or conveyor of a stationary or movable type, as may be desired, and of the desired length. 30 In the figure illustrated I have shown a movable conveyor belt which is carried by the end pulleys 9 and 10, and which may be driven in any suitable manner. There are also provided forming rolls 11 and 12 of the desired size, shape and material, and which may be supported in any suitable manner, preferably so that they may be relatively adjusted so as to vary the thickness of the manufactured board. Arranged 40 at each side of the conveyor are side boards or plates 13 which are the desired distance apart, this depending upon the size of the plaster board to be made. Preferably they are so spaced apart that the distance between them equals the width of the board, so that the covering sheets and plaster run 45 between the same, whereby they accurately gauge the paper, one above the other, and at the same time retain the plaster, prevent 50 its flowing out beyond the edges and smooth the edges. The covering sheets, as before mentioned may be of any desired material, paper being generally employed for the purpose, which paper is of the desired make-up and which is generally supplied in rolls, 55 for example, rolls 14 and 15 as shown in the figure. Arranged between the forming rolls and paper rolls are cutters 16 and 17, arranged to cooperate and trim the opposite 60 sides of the two covering sheets to the exact

desired widths. These trimmers or cutters are made laterally adjustable so that the exact widths of the trimmed sheets and their exact location with reference to the edges and the plaster board machine into 70 which it is being fed can be adjusted at the will of the operator. The trimmed off portions 2' and 3' at each side of the sheet shown in Fig. 3 are simply discarded and removed from time to time from the vicinity of the machine. I have shown cover sheet 2 extending over the conveyor, but cover sheet 3 I extend over a roll 19 and under a roll 18. The same, after extending 75 over the roll 19, is extended through a guide 80 20 of the desired size and shape, which feeds the same under the roll 12 so that it may be applied as the top sheet of the board. It will be noted that the sheet is curved so that it is stiffened and consequently may be 85 accurately fed to the plaster and bottom sheet. By separating the two sheets as shown in Fig. 1, the plaster 21 may be applied between the sheets in the desired quantities and mix. The top and bottom sheets 90 being of exactly the same width at all times, they will also lap exactly over each other in a perpendicular position so that the edge of the top one is directly over the edge of the other.

Referring to Fig. 2, the machine illustrated is substantially similar to that shown in Fig. 1 and the method practically the same, except the machine is here equipped to produce the board with the reinforced 100 edge. This is accomplished by providing a guide 22 into which the ends 2' and 3' of the trimmings are fed and thence over between the sheets and into the body. The trimmings may be started in the guide, and 105 inserted in the board by hand or any desired manner. After the trimmings have been properly started in between the sheets of the board, the same will be fed along or drawn through by the advancing board 110 and form an edge with the desired number of layers between the cover sheets, that is to say, one, two or more as desired. If additional reinforcing strips are desired other than the two trimmed edges at each 115 side, additional strips may be fed in.

In the construction shown in Figs. 4 and 5, Fig. 4 illustrates a modified type illustrated to make the board shown in Fig. 8, while Fig. 5 illustrates substantially the 120 same machine slightly modified to produce the board shown in Fig. 9. Referring to Fig. 4, the reference characters 7, 9, 10, 11, 12 and 13 represent mechanisms similar to that previously described. In this case, 125 however, the lower sheet 26 is taken from a roll 25, the same being trimmed to the desired width by the trimmers 27 arranged at each side, or equivalent mechanism for the purpose. The upper sheet 29 is taken 130

from roll 28, the same being trimmed by the trimmers 30 or their equivalents. The two sets of trimmers are preferably made laterally adjustable so that they may be controlled by the operator in order to produce the desired product, it being possible for him to shift one or the other slightly or to the desired extent so as to bring one sheet directly over the other, their widths of course being substantially or exactly the same. In this case the trimmings may be discarded if desired. In Fig. 5, I have illustrated a guide 31 at each side into which the trimmings 26' may be fed into and may be imbedded in the plaster, and a similar guide 32 for guiding the trimmings 29' in the same manner. With all of the constructions illustrated it will be noted that the papers are trimmed substantially just before going through the forming rolls, so that they are practically in all cases the same exact width, it being possible to so control the trimming mechanism and method of trimming that they pass between the forming rolls in exactly the desired relation, thereby producing a uniform and attractive appearing product. The various trimmers, as stated, are made adjustable as desired so that they may be controlled at the will of the operator or automatically to produce the desired product. Obviously any equivalent apparatus may be employed to carry out the method or process described.

I have illustrated in Figs. 10, 11 and 12 one form of trimming mechanism in which the cutters are laterally adjustable relative the paper as well as relative each other, so that the trimming may be varied as found necessary, both in setting the machine and during the operation thereof. Referring to these figures, 40 and 41, and 42 and 43 represent the trimmers which may be of suitable size, shape, construction and material. The trimmers shown are mounted on shafts 44 and 45, the same being adjustable thereon, and the shafts may be driven by any suitable power or the paper only drawn therethrough. The shafts are rotatably carried by brackets 48 or their equivalent. Arranged to control the positions of the cutters are brackets 46 and 47 of the desired size, shape, construction and material. In the construction shown, the brackets 46 and 47 are operatively connected by a threaded rod 51, which may be controlled by the hand wheel 52, or equivalent means. Obviously, by manipulating shaft 51, the two sets of cutters may be separated or brought closer together, as may be desired. I have shown a threaded rod 49, provided with a hand wheel 50, which is operatively connected with one of the brackets, as shown by bracket 46, so that the cutters may be adjusted in either direction laterally in unison as desired. Obviously,

by manipulating one or the other of the hand wheels 50 or 52, singly or by operating them together in the same or in different directions, the cutters may be controlled either in unison or separately to produce the desired result. While I have illustrated but one form of trimming mechanism, the same may be accomplished as desired.

With the board shown in Fig. 8, it will be noted that a straight edge or side 4 is formed at each edge side of the board, the extreme edges of the cover sheets 2 and 3 being directly aligned one above the other, with a plastic body which comes flush with the two edges of the covering sheets.

The reinforced board shown in Fig. 9 is substantially the same except that the trimmed portions 3' and 2' are imbedded in the edges of the board, being so fed into the body as described, that their outer edges are flush with the extreme edges of the two covering sheets 2 and 3. Obviously, their widths will depend upon the width of the strips trimmed from the papers or covering sheets and may be made as desired depending upon the width of the separated product and the width of the paper supplied. It will likewise be obvious that any additional reinforcing strips may be inserted. It will be noted that in this case, while the edges of the board are reinforced, yet the main body of the board is not divided or separated as in the case of wide sheets inserted between the cover sheets, the portions between one cover sheet and the trimmed portions 2' and 3' being connected with the body and with each other. Either of the boards are extremely pleasing in appearance and also being true or perfectly formed at the edges, and may be put together end to end or side to side as the case may be, the same giving a perfect finished wall, ceiling or the like. With the form shown in Fig. 9, nails may be driven through more pieces of the fabric or covering material, and a slight crumbling between any of the reinforcing strips or covering sheets will not materially affect the strength of the edge nor the appearance. The same is also more durable showing that a better product is produced.

Having thus described my invention, it is obvious that various immaterial modifications may be made in the same without departing from the spirit of my invention; hence I do not wish to be understood as limiting myself to the exact method, form of apparatus or board, arrangement, construction and combination of parts herein shown and described, or uses mentioned.

What I claim as new and desire to secure by Letters Patent is:

1. A method of making a plaster board consisting in bringing together and trimming two cover sheets at the same time to

- 4
- exact widths and applying a body of plastic material between them just after the trimming, and pressing the sheets and body together to form a board of the desired thickness. 5
2. A method of making a plaster board consisting in bringing together and trimming a plurality of sheets of covering material at the same time to exact widths and applying a mass of plaster between them just after the trimming, and thereafter pressing the sheets and mass together to form a board of the desired thickness. 10
3. A method of making a plaster board consisting in bringing together and trimming two sheets at the same time to exact widths, applying a plastic mass on one sheet just after the trimming, and moving and pressing the sheets and mass together with the edges of the upper sheet positioned directly above and with its edge in alignment with the edge of the other sheet, and confining the plastic mass at the said edges between the sheets. 15
4. A method of making a plaster board consisting in bringing together and trimming two sheets at the same time to exact equal widths, applying a plastic mass of plaster on one sheet just after the trimming, and thence applying the second sheet to the top of the plaster with its two side edges directly above the side edges of the lower first sheet, thence pressing the sheets together at the same time preventing the escape of the plaster at the edges. 20
5. A method of making plaster board consisting in bringing together and trimming at the same time two sheets of the same width, arranging said sheets one above the other, and applying a plastic mass between them just after the trimming, retaining the mass and preventing its escaping beyond the side edges of the sheets and applying pressure to the sheets to bring the two together with the plaster between them, with the side edges of one directly aligned with the side edges of the other. 25
6. A method of making plaster board having a body and cover sheets adhering thereto, comprising the advancing of the bottom sheet towards board forming roll, trimming said sheet the exact width of the board desired as it advances, depositing the body in plastic form on the trimmed sheet, advancing the upper cover sheet towards the forming roll, trimming said sheet placed together with and at the same time as the first sheet, the exact width of the board desired as it advances, applying the said sheet over the body, passing the body and cover sheets under the forming roll, and maintaining the edges of the cover sheets in alignment one above the other and retaining the body in line therebetween. 30
7. A method of making plaster board having a body with cover sheets adhering thereto, comprising bringing the sheets together and advancing them towards a board forming device, trimming both sheets at the same time the exact width of the board desired, separating the sheets, depositing the body in plastic form between the sheets and passing the sheets with the plastic body between them through the board forming device. 70
8. A method of making plaster board having a body with cover sheets adhering thereto, comprising bringing the sheets together and advancing them towards a board forming device, trimming both sheets at the same time the exact width of the board desired, depositing the body in plastic form between said sheets just after the trimming, guiding the trimmed sheets to maintain their edges in alignment one above the other, passing the aligned sheets with the plastic body between them through board forming rolls, and maintaining the plastic body between the aligned edges of the sheets. 80
9. A method of making plaster board with covering sheets and a plaster body arranged therebetween, consisting in first bringing the sheets together and trimming the side edges of the two sheets while together, whereby said sheets are both cut the same width, thence separating the sheets and applying a plastic mass between them, thence again bringing the two sheets substantially together with the mass between, with the trimmed edges of one sheet lying directly above the trimmed edges of the other and forming the board of the desired thickness, at the same time preventing the escape of the plastic mass from between the sheets at their edges and preventing weaving of one sheet relatively to the other. 90
10. A method of making plaster board consisting in first trimming two sheets to exact widths, applying a plastic mass therebetween, and applying the trimmings to the plastic mass and between the sheets adjacent the edges thereof, whereby the same are imbedded in the mass, and thereafter pressing the sheets, plastic mass and trimmings to produce a board of the desired thickness. 100
11. A method of making plaster board consisting in bringing together into contact and then trimming a plurality of sheets of covering material to a desired width, applying a plaster between them with reinforcing strips at the edges between the sheets. 110
12. A method of making plaster board consisting in trimming two sheets to the desired relative widths, applying a plastic mass on one sheet and applying trimmings to the plastic mass at the edges of the sheets, whereby the same are imbedded in the mass and thereafter applying the other 120
- 130

sheet and pressing the sheets and plastic mass and trimmings together to produce a board of the desired thickness.

13. A method of making plaster board consisting in first bringing together and trimming two sheets to exact widths, applying a plastic mass therebetween, and applying strips of the sheet material to the plastic mass and between the sheets adjacent the edges thereof, whereby the same are imbedded in the mass, and thereafter pressing the sheets and plastic mass and strips to produce a board of the desired thickness.

14. A method of making plaster board consisting in bringing together and at the same time trimming two sheets to the desired relative widths, applying a plastic mass on one sheet, applying strips of fibrous material to the plastic mass at the edges of the sheet, whereby the same are imbedded in the mass, and thereafter applying the other sheet, and pressing the sheets and plastic mass and fibrous strips together to produce a board of the desired thickness.

15. In a machine of the kind described and in combination, a suitable conveyor, means for applying sheets of covering material to the conveyor, means for trimming said covering sheets to equal widths whereby the sheets may be arranged with their side edges substantially in alignment, means for depositing a plastic mass on one sheet, means for conveying the other covering sheet onto said plastic mass, means for applying strips of material trimmed from said sheets by said trimming means to the plastic mass between said sheets whereby the same is imbedded in the mass, and forming mechanism arranged at said conveyor for forming the covering sheets and plastic mass in a board of the desired thickness.

16. In a machine of the kind described and in combination, a suitable conveyor, means for applying sheets of covering material to the conveyor, means for trimming said covering sheets to equal widths whereby the sheets may be arranged with their side edges substantially in alignment, means for depositing a plastic mass on one sheet, means for conveying another covering sheet onto said plastic mass, means for applying strips of material trimmed from said sheets by said trimming means to the plastic mass between said sheets whereby the same is imbedded in the mass, forming mechanism arranged at said conveyor for forming the covering sheets and plastic mass in a board of the desired thickness, and means for confining the plastic material between the sheets prior to its initial setting and smoothing the exposed edges thereof.

17. In a machine of the kind described and in combination, a suitable support, a forming mechanism arranged on said support, means for applying a sheet of covering ma-

terial to the support, means for depositing a plastic mass on said sheet, means for conveying a second covering sheet onto said plastic mass, said machine provided with means for bringing together and then trimming said cover sheets to desired relative widths, means for retaining the sheets in position whereby the sheets are arranged with their side edges substantially exactly in alignment, and means for applying strips of said sheet material to the plastic mass between the sheets whereby the same are imbedded in the mass.

18. In a machine of the kind described and in combination, a suitable conveyor, means for applying sheets of covering material to the conveyor, means for bringing together and then trimming said covering sheets to equal widths whereby the sheets may be arranged with their side edges in alignment, means for depositing a plastic mass on one sheet, means for conveying the other covering sheet onto said plastic mass, and means for applying strips of cover sheet material to the plastic mass between said sheets whereby the same are imbedded in the mass, and forming mechanism arranged at said conveyor for forming the covering sheets and strips and plastic mass in a board of the desired thickness.

19. In a plaster board machine, forming mechanism, means for supplying cover sheets to the forming mechanism, means for depositing plastic material between the sheets in advance of the forming mechanism, and mechanism for simultaneously trimming while in contact the edges of the sheets previously brought into contact in advance of the depositing means.

20. In a plaster board machine of the kind described and in combination, a suitable support, forming mechanism, means for supplying cover sheets to said forming mechanism, and means in advance of said forming mechanism for bringing together and trimming the side edges of the sheets.

21. In a plaster board machine of the kind described and in combination, forming mechanism, and means for bringing together and trimming sheets of cover material supplied to said forming mechanism, whereby the sheets are fed into the forming mechanism in a predetermined manner relative to each other and gauged relative the forming mechanism, said trimming means being arranged at each side of the sheets for trimming the side edges of the sheets while they are in contact with each other whereby the sheets are fed to the forming mechanism in a predetermined manner regardless of the initial width of the sheet before trimming or the feeding of the same prior to trimming.

22. In a plaster board machine of the kind described and in combination a suitable support, forming mechanism, means for advancing a cover sheet of cover material upon the

- support, means for trimming said sheet the exact width of the board desired as it advances, means for advancing a second sheet of cover material to the forming mechanism, said second sheet being trimmed in contact and together with the first sheet as they advance the exact width of the board desired, and means for passing both sheets through said forming mechanism.
- 10 23. In a plaster board machine of the kind described and in combination, a suitable support, a forming mechanism at said support, means for advancing cover sheets together towards said forming mechanism, mechanism mounted in advance of the forming mechanism for trimming the side edges of both sheets at the same time, while in contact, and means for depositing a plastic body between the sheets just after being trimmed 20 and before passing through the forming mechanism.
24. In a plaster board machine of the character described and in combination, a suitable support, a forming mechanism at said support, means for advancing cover sheets together towards said forming mechanism, mechanism mounted in advance of the forming mechanism for trimming the side
- edges of both sheets at the same time while in contact, means for separating the sheets, 30 means for depositing a plastic mass between the trimmed sheets, and means bringing the sheets together and passing the sheets with the plastic mass between them through the forming mechanism.
25. In a plaster board machine of the kind described and in combination, a suitable support, forming mechanism, means for supplying cover sheets to said forming mechanism, and mechanism at each side of the 40 machine in advance of said forming mechanism for trimming the side edges of said sheets, said trimming mechanism being laterally adjustable in unison and independently.
26. In a plaster board machine of the kind described and in combination, means for advancing cover sheets and bringing them together into contact before forming the board, and adjustable trimming cutters at 50 each side to trim the cover sheet together at the same time while they are in contact.

In testimony whereof, I have hereunto signed my name.

CHARLES R. BIRDSEY.
